Primary Examiner — Rosemary K Tarcza*Assistant Examiner* — Seth David Kumpf*(74) Attorney, Agent, or Firm* — Foley & Lardner LLP(57) **CLAIM**

The ornamental design for a battery charger pedestal, as shown and described.

DESCRIPTION

FIG. 1 is a front-right perspective view of the battery charger pedestal of the present disclosure;

FIG. 2 is a front elevational view of the battery charger pedestal of the present disclosure (the rear elevational view is a mirror image);

FIG. 3 is a right elevational view of the battery charger pedestal of the present disclosure (the left elevational view is a mirror image);

FIG. 4 is a top plan view of the battery charger pedestal of the present disclosure; and,

FIG. 5 is a bottom plan view of the battery charger pedestal of the present disclosure.

The broken lines shown in the drawings are for the purpose of illustrating portions of the battery charger pedestal that form no part of the claimed design.
